MILL

Louis S. Petersen, Forest Hills, N. Y., assignor to
 F. L. Smith & Co., New York, N. Y., a corporation of New Jersey

Application October 11, 1943, Serial No. 505,729

12 Claims.

(Cl. 74—421)

This invention relates to apparatus of the type that includes a generally cylindrical shell mounted for rotation on its longitudinal axis, examples of such apparatus being ball mills, rotary kilns, certain forms of dryer, etc. More particularly, the invention is concerned with a novel apparatus of the kind mentioned which is superior to prior equipment with respect to the means by which the shell is supported and rotated. While the new apparatus may take various forms, as indicated above, the invention may be embodied to especial advantage in ball mills and its application to that field will, accordingly, be illustrated and described in detail for purposes of explanation.

Ball mills consist essentially of a generally cylindrical shell or drum mounted with its longitudinal axis horizontal and supported for rotation on that axis. The shell is closed at its ends and is provided with an inlet at one end through which material to be ground may be introduced by appropriate means, such as a rotary scoop within a casing, and with an outlet at the other end through which the ground material is discharged.

In one prior construction, the shell is formed with hollow trunnions at its ends serving, respectively, as the inlet and the outlet, and the shell is supported by bearings in which the trunnions run. The shell is then rotated by a master gear which encircles and is secured to the drum and is enclosed within a casing. This construction, in which the entire weight of the drum and its contents is carried by the trunnions and their bearings, is relatively expensive because of the large trunnion bearings required. Also, since the shell is supported beyond its ends, difficulties may arise because of misalignment caused by warping or buckling of the shell, the heads, or the trunnions as a result of operation or temperature conditions.

In another prior mill, one of the trunnion bearings is eliminated and the shell is provided near its inlet end with a slide ring mounted on slide shoes, the ring and shoes being enclosed within a casing. This construction is less expensive than the mill provided with the two trunnion bearings, but is objectionable by reason of the necessity of providing three casings, one for the inlet scoop, one for the slide ring and shoes, and one for the master gear and driving pinion. In a further development of the mill of the second type, the slide ring with its shoes is placed centrally of the drum so as to bear substantially the entire load. This permits replacement of the trunnion bearing

by a small guide bearing, so that the cost of construction is reduced, but again, the mill includes the three casings above mentioned.

The present invention is directed to the provision of a mill or similar apparatus including a generally cylindrical shell mounted for rotation on its longitudinal axis which is superior to the prior constructions described in that it is lower in cost and simpler in erection, and those parts which require attention and lubrication are more readily accessible. At the same time, difficulties arising from misalignment of the parts because of warping or buckling are largely eliminated.

In the new apparatus in the form, for example, of a ball mill, the shell has an inlet at one end, which may be provided with an inlet scoop of usual construction, has an outlet at the other end, and has a guide bearing at one end to prevent the mill from tilting. Between its ends, the mill is encircled by a ring which is secured to the shell and has a periphery formed with adjacent circumferential sections, one of which has a smooth surface and another of which is formed as a gear. The shell is rotated by means of a pinion meshing with the teeth of the gear section and it is supported for rotation on supporting means engaging the smooth section. With the driving and supporting means placed close together at the middle of the shell, these parts can all be enclosed within a single casing. Preferably, the ring encircling the shell is formed with a pair of gear sections which may have teeth corresponding, respectively, to the two halves of a herringbone gear. When two gear sections are employed, the shaft carries two pinions and is supported in a bearing lying between the pinions and in alignment with the smooth section of the ring. This bearing is self-aligning at least in a plane generally parallel to the direction of tooth pressure, and the gears, consequently, take part equally in the driving of the drum so that undue wear is eliminated.

For a better understanding of the invention, reference may be had to the accompanying drawings in which:

Fig. 1 is a view in side elevation, with parts shown in section on the line 1—1 of Fig. 2, of one form of apparatus constructed in accordance with the invention;

Fig. 2 is a sectional view of the apparatus shown in Fig. 1 on the line 2—2 of Fig. 3;

Fig. 3 is another sectional view on the line 3—3 of Fig. 2; and

Figs. 4 and 5 are fragmentary elevational views.

with parts shown in section, of modified constructions.

The ball mill shown in Fig. 1 includes a generally cylindrical shell 10 having end sections 11 and 12. Section 11 is provided with a tubular inlet 13 for material supplied thereto by means of a rotating scoop 14, the inlet containing flights 15 for advancing material through it. The scoop is mounted between the tubular inlet 13 and the short shaft 16 which is supported in the bearing 17 on a standard 18. This bearing, which is only for the purpose of preventing the mill from tilting about the main support, carries little or no load and can, therefore, be of very small size. If preferred, a trunnion bearing may be provided between the scoop and the mill body, in which event, the shaft 16 and its bearing 17 may be eliminated. The scoop dips into a body of material 19 contained within a pit 20 and is enclosed within a casing 21 provided with appropriate means for sealing the shaft and the outside of inlet 13. The end section 12 is provided with a tubular outlet 22 which extends into the stationary discharge casing 23. The shell, the scoop, and the other features above described are of conventional construction.

Encircling the shell substantially midway between its ends is a ring 24 which is provided with an inwardly extending web 25 which may be bolted to brackets 26 welded or otherwise secured to the outer surface of shell 10. The member 24 has a smooth peripheral section 27 lying between adjacent peripheral sections 28, both of which are formed with gear teeth, and, in the construction shown, the outer diameter of the smooth section is less than that of the gear sections. It will be understood, however, that the smooth section may be of the same outer diameter as the gear sections or of greater diameter, as desired. Extending inward radially along each edge of ring 24 is a flange 29 and the ring is reinforced by webs 30 extending from the inner surface of each flange and the under surface of the periphery of the ring to web 25.

The smooth section 27 of ring 24 may serve as a tire running on supporting rollers or as a slide ring sliding on shoes. The latter construction is illustrated and the smooth section runs on slide shoes 31 supported on standards 32 on a foundation 33. Preferably each shoe is mounted for universal movement and, for this purpose, it is provided on its under surface with a ball shaped insert 34 resting in a cup 35 on the top of the standard 32.

The shell is rotated by means of a pair of pinions 36 mounted on a shaft 37. In the construction shown in Fig. 1, the gear sections 28 have teeth similar, respectively, to those of the halves of a herringbone gear and the pinions 36 have teeth of appropriate shape to mesh with the gear sections. Shaft 37 is mounted in a bearing 38 between the pinions and the bearing preferred for the purpose is one which is self-aligning in the plane of tooth pressure. Shaft 37 is connected at one end through a flexible coupling 39 to a shaft 40 running in a bearing 41 on the foundation 42 and connected through a flange coupling 43 to the shaft of the driving motor 44. The weight of half the coupling 39 attached to one end of shaft 37 tends to cause the shaft to tilt in its bearing 38 and this tendency may be overcome by applying a counterweight to the other end of the shaft or subjecting it to spring pressure. The latter construction is illustrated

and it includes a bearing 45 in which the free end of the shaft runs and which is pressed downwardly by a spring 46. The pressure of the spring is adjustable by a screw 47 mounted in the wall of casing 48 surrounding the end of the shaft and the spring serves to equalize the load on opposite ends of the shaft.

The ring 24, with its smooth and gear sections, the driving pinions 36, and the slide shoes 31 and their supports are all enclosed within a casing 49 which encircles the shell. This casing prevents access of dust to the pinions, gear sections, and slide shoes and is provided with sealing means, such as felt rings 50 bearing on flanges 29 on ring 24, and sealing ring 50a bearing on the surface of shaft 31. As ring 24 serves as part of both the driving and supporting means, a single casing is sufficient to enclose these two means. The casing rests on the foundation 33 and may be made of a number of parts bolted together, as indicated in Fig. 2, so that by removal of one or more parts of the casing, access may be readily had to the pinions, bearing 38, and the slide shoes 31.

In the construction shown in Figs. 1 to 3, the ring 24 is preferably made in one piece so that it completely encircles the shell and may be secured thereto by bolts. However, the ring may be made in sections, each of which is preferably a single section, although each section may be made of two or more pieces bolted or otherwise secured together.

In the mill shown in Fig. 1, the weight of the shell and its contents is borne substantially entirely by the shoes 31 sliding on the smooth section 27 of ring 24. If this section is of less outer diameter than the gear sections 28 on either side thereof, additional space is provided opposite the smooth section for the bearing 38 of shaft 37 carrying the driving pinions 36. The bearing 38 is self-aligning as described and, as a result, the same tooth pressure is obtained on each pinion.

In the construction shown in Fig. 4, the shell 51 is provided as before with an inlet at one end receiving material from a scoop, and an outlet to the other. The shell is encircled by a ring 52 having a smooth central section 53 and gear sections 54 on either side thereof. The gear sections illustrated have teeth of the spur type and these teeth mesh with similar teeth on pinions 55 on a shaft 56 supported in a bearing 57 between the pinions and mounted on a block 58. Shaft 56 is also mounted in another bearing 59 and is connected through a coupling 60 to the shaft of a motor 61. The shell 51 may be supported for rotation on rollers or on slide shoes acting on the smooth section 53 of ring 52 and it is rotated by pinions 55 meshing with gear sections 54. The supporting means for the shell, the ring 52, and the pinions 55 and associated parts are enclosed within a single casing 62 supported on the foundation 63. In the construction shown in Fig. 4, the bearing 57 is not self-aligning, but a bearing similar to bearing 38 of Fig. 1 may be employed with this construction, provided shaft 56 is divided into two sections similar to shafts 37 and 40 and coupled by a flexible coupling, the free end section being suitably balanced.

In some instances, it may be desirable to provide only a single master gear for rotating the shell and such a construction is illustrated in Fig. 5. In that construction, the ring 64 encircling shell 65 has a smooth section 66 and a single gear section 67. A pinion 68 on a shaft

69 mounted in bearings 70 and 71 engages gear 67 and the smooth section 66 serves as the slide ring for slide shoes 72. The member 64, the slide shoes, pinion, and shaft bearing 70 are all mounted within a single casing 73 which prevents dust from reaching these parts.

In the new mill, the provision of a single member, such as ring 24 which includes both a smooth section serving as a slide ring or a tire, and one or two gear sections, simplifies the construction and reduces the cost. This ring, together with the supporting means and driving pinions, can be enclosed within a single casing through which access may be had to the supporting and driving means for lubrication and other care. The construction described is simpler in erection and requires simpler foundations than prior similar mills and by bringing all the elements of the driving and supporting means into one integral unit, misalignment resulting from warping or buckling of the shell, the heads, and other parts caused by operating or temperature conditions or by uneven settlement of foundations is largely eliminated.

I claim:

1. Apparatus of the type described, which comprises a generally cylindrical shell, a member encircling and secured to the shell and having adjacent peripheral sections, one having a smooth surface and another formed as a gear, a foundation, supporting means on the foundation engaging said smooth section to support the shell for rotation, a shaft, a pinion on the shaft meshing with the gear section to rotate the shell, and a casing on the foundation encircling the shell and enclosing the member, supporting means, and pinion, the shaft extending through the wall of the casing.

2. Apparatus of the type described, which comprises a generally cylindrical shell, a member encircling and secured to the shell and having adjacent peripheral sections, one having a smooth surface and another formed as a gear, a foundation, slide shoes mounted on the foundation and engaging said smooth section to support the shell for rotation, a shaft, a pinion on the shaft meshing with the gear section to rotate the shell, and a casing on the foundation encircling the shell and enclosing the member, shoes, and pinion, the shaft extending through the wall of the casing.

3. Apparatus of the type described, which comprises a generally cylindrical shell, a member encircling and secured to the shell and having adjacent peripheral sections, one having a smooth surface and another formed as a gear, the outer diameter of the smooth section being less than that of the gear section, a foundation, supporting means on the foundation engaging said smooth section to support the shell for rotation, a shaft, a pinion on the shaft meshing with the gear section to rotate the shell, and a casing on the foundation encircling the shell and enclosing the member, supporting means, and pinion, the shaft extending through the wall of the casing.

4. Apparatus of the type described, which comprises a generally cylindrical shell, a member encircling and secured to the shell and having adjacent peripheral sections, one having a smooth surface and another formed as a gear, the outer diameter of the smooth section being less than that of the gear section, a foundation, slide shoes mounted on the foundation and engaging said smooth section to support the shell for rotation,

a shaft, a pinion on the shaft meshing with the gear section to rotate the shell, and a casing on the foundation encircling the shell and enclosing the member, shoes, and pinion, the shaft extending through the wall of the casing.

5. Apparatus of the type described which comprises a generally cylindrical shell, a member encircling and secured to the shell and having a pair of peripheral gear sections and a smooth surfaced peripheral section between the gear sections, a foundation, supporting means on the foundation engaging the smooth section and supporting the shell for rotation, a shaft, a pair of pinions on the shaft meshing with respective gear sections to rotate the shell, and a casing on the foundation encircling the shell and enclosing the member, supporting means, and pinions, the shaft extending through the wall of the casing.

6. Apparatus of the type described which comprises a generally cylindrical shell, a member encircling and secured to the shell and having a pair of peripheral gear sections and a smooth surfaced peripheral section between the gear sections, the outer diameter of the smooth section being less than that of the gear sections, a foundation, supporting means on the foundation engaging the smooth section and supporting the shell for rotation, a shaft, a pair of pinions on the shaft meshing with respective gear sections to rotate the shell, and a casing on the foundation encircling the shell and enclosing the member, supporting means, and pinions, the shaft extending through the wall of the casing.

7. Apparatus of the type described which comprises a generally cylindrical shell, a member encircling and secured to the shell and having a pair of peripheral gear sections and a smooth surfaced peripheral section between them, the gear sections having teeth of the shape of those of respective halves of a herringbone gear, a foundation, supporting means on the foundation engaging the smooth section and supporting the shell for rotation, a shaft, a pair of pinions on the shaft meshing with respective gear sections to rotate the shell, and a casing on the foundation encircling the shell and enclosing the member, supporting means, and pinions, the shaft extending through the wall of the casing.

8. Apparatus of the type described which comprises a generally cylindrical shell, a member encircling and secured to the shell and having a pair of peripheral gear sections and a smooth surfaced peripheral section between them, a foundation, supporting means on the foundation engaging the smooth section and supporting the shell for rotation, a shaft, a bearing for the shaft lying in alignment with the smooth section, pinions on the shaft meshing with the gear sections, and a casing on the foundation encircling the shell and enclosing the member, supporting means, bearing, and pinions, the shaft extending through the wall of the casing.

9. Apparatus of the type described which comprises a generally cylindrical shell, a member encircling and secured to the shell and having a pair of peripheral gear sections and a smooth surfaced peripheral section between them, a foundation, supporting means on the foundation engaging the smooth section and supporting the shell for rotation, a shaft, pinions on the shaft meshing with the gear sections to rotate the shell, a single bearing for the shaft, the bearing lying between the pinions, and a support on the foundation on which the bearing is mounted for self-

aligning movement in a plane generally parallel to the plane of pinion tooth pressure.

10. Apparatus of the type described which comprises a generally cylindrical shell, a member encircling and secured to the shell and having a pair of peripheral gear sections and a smooth surfaced peripheral section between them, a foundation, supporting means on the foundation engaging the smooth section and supporting the shell for rotation, a shaft, pinions on the shaft meshing with the gear sections to rotate the shell, a single bearing for the shaft, the bearing lying between the pinions and mounted on the foundation for self-aligning movement in a plane generally parallel to the plane of pinion tooth pressure, a second shaft aligned with the pinion shaft, connected coupling members on the adjacent ends of the shafts, and means engaging the other end of the pinion shaft to balance the weight of the coupling member carried thereby.

11. Apparatus of the type described which comprises a generally cylindrical shell, a member encircling the shell and having adjacent peripheral sections, one having a smooth surface and another formed as a gear, the member having a web extending inwardly and secured to the shell, a foundation, supporting means on the founda-

tion engaging the smooth section and supporting the shell for rotation, a shaft, a pinion on the shaft meshing with the gear section to rotate the shell, a bearing for the shaft in alignment with the smooth section, and a casing on the foundation enclosing the member, pinions, bearing, and supporting means, the shaft extending through the wall of the casing.

12. Apparatus of the type described, which comprises a generally cylindrical shell, a member encircling and secured to the shell and having adjacent peripheral portions, one having a smooth surface and another formed as a gear, a foundation, supporting means on the foundation engaging the smooth section to support the shell for rotation, a shaft, a pinion on the shaft meshing with the gear section to rotate the shell, a self-aligning bearing for the pinion shaft, a drive shaft, a coupling connecting one end of the pinion shaft and the drive shaft, means acting on the other end of the pinion shaft for counterbalancing the weight of the portion of the coupling secured to the pinion shaft, and a casing encircling the shell and enclosing the member, supporting means, and pinion, the pinion shaft extending through one wall of the casing.

LOUIS S. PETERSEN.
